(57) **CLAIM**

The ornamental design for a guide member for an arm rest apparatus, as shown and described.

DESCRIPTION

FIG. 1 is a front view of a guide member for an arm rest apparatus, of our new design;

FIG. 2 is a rear view of the guide member shown in FIG. 1; FIG. 3 is a top view of the guide member shown in FIG. 1; FIG. 4 is a bottom view of the guide member shown in FIG. 1;

FIG. 5 is a left side view of the guide member shown in FIG. 1;

FIG. 6 is a right side view of the guide member shown in FIG. 1;

FIG. 7 is a perspective view of the guide member shown in FIG. 1;

FIG. 8 is a view for a reference, which shows an expanded state of the guide member;

FIG. 9 is a view for a reference, which shows a part of an enlarged guide member corresponding to the guide member shown in FIG. 1;

FIG. 10 is a view for a reference, showing an arm rest apparatus in which a guide member corresponding to the guide member shown in FIG. 1 is attached;

FIG. 11 is a view for a reference, which shows a position relationship of the arm rest apparatus with respect to an arm; and,

FIG. 12 is a view for a reference, which shows a using state of the arm rest apparatus.

The broken line showing is included for the purpose of illustrating unclaimed subject matter and environment, and forms no part of the claimed design.
